UNITED STATES PATENT OFFICE

NATHAN LESTER, OF WORCESTER, MASSACHUSETTS

PNEUMATIC CASTING PUMP

Application filed April 6, 1928. Serial No. 268,019.

This invention relates to a casting pump of the gooseneck variety principally for use in die casting machines.

The principal objects of the invention are 5 to provide an improved motion for dipping the gooseneck into the molten metal in the pot and bringing it up out of the melting pot and into casting position; to provide an arrangement by which the motion of the 10 parts and the setting of the nozzle into casting position will be independent of and unaffected by the expansion and contraction of the metal under different heat conditions, and to provide a construction in which the pump 15 itself can be set down into a cradle forming a support therefor and removed therefrom readily without taking out any of the rest of the mechanism.

The invention also involves improvements 20 in features of construction and combinations of parts as will appear.

Reference is to be had to the accompanying drawings in which

Fig. 1 is a side view of a melting pot and 25 pneumatic pump in position for casting, constructed in accordance with this invention;

Fig. 2 is a plan of the same;

Fig. 3 is a view similar to Fig. 1 showing 30 the pneumatic pump drawn back from the dies and in position for filling it with molten metal;

Fig. 4 is a plan of the cradle and pump on enlarged scale showing details of construction;

Fig. 5 is a central longitudinal sectional view on the line 5—5 of Fig. 4, but showing 35 the pump itself in side elevation;

Fig. 6 is a sectional view of a detail on the line 6—6 of Fig. 4, and

Fig. 7 is an end view of a detail as indicated 40 by the arrow 7 in Fig. 3.

Although capable of other uses, the invention is illustrated as cooperating with a melting furnace 10, a melting pot 11 and a wall 45 12 supporting one of the dies of a die casting machine. The dies and details of the mold are not illustrated herein as they do not constitute a feature of this invention.

However, it may be stated that a rod 13 50 is intended to be connected with the movable

die member and to move therewith back and forth so that when the die is closed the rod will be moved to the position shown in Figs. 1 and 2. It operates a shaft 15 having a crank arm 14 connected to the rod by a bolt 55 and slot connection 16. The shaft 15 is mounted in suitable bearings on a pair of slides 17. These slides are shown as having an inverted T-shape base freely movable in horizontal guides 18, which are mounted on the furnace.

The shaft 15 is provided with a crank arm 20 connected with a link 21 for operating the cradle 22. The cradle is provided with a pair of rods or guides 19 fixed in collars 23 loosely 65 mounted on the shaft. These rods provide a rigid straight line support for the cradle. At the other end these rods 19 are mounted in cylindrical lugs 24 on the cradle frame, which is 60 slideable on the rods.

The cradle frame is provided with a lug 25 pivoted at the top by a pin 26 to a vertical link 27. This link, by a pin 28 is pivoted to an adjusting plate 29 having adjusting screws 30 at either end adapted to rest down on the 70 top of the furnace. This plate 29 is pivoted at 31 to a lug projecting upwardly from the top of the furnace. By means of these screws 75 it can be adjusted in any desired position to get just the right height for the pins 28 and 26. The pin 26 serves as a movable supporting pivot for the cradle as will be seen from 80 a comparison of Figs. 1 and 3. This supporting mechanism is located on one side of the furnace only but the two rods 19 both serve 85 the same purpose.

This cradle 22 is provided with a notch 32 for receiving the end of the pneumatic pump or gooseneck 33 and with screws 34 for adjusting the position thereof or rather tightening it in adjusted position. The cradle 22 is of a U-shaped construction, the two legs of which have open top notches 35 facing each other at their inner ends and adapted to receive in them the ends of a pivot rod 36 90 which is part of the gooseneck and is fixed thereto. Adjusting screws 37 pass through the end of the legs of the cradle and adjust and hold the pivot rod in central position. The height of the gooseneck is accurately ad- 95 100

justed by screws 38, as shown in Fig. 6. The gooseneck is provided with a space for receiving the metal and with a metal discharge spout 41 and nozzle 39. This nozzle is adapted to fit against a conduit 40, which conducts the metal into the dies held on the back of the plate 12.

Also, at the top of the pneumatic pump is a cap 42. This cap is held on by a yoke 43 having a holding screw 44 and provided at the ends of its legs with hooks, not shown, extending inwardly to hold the cap in position. This cap has a conduit 45 having a nozzle 46 fitting against a plate 47 and adapted to receive a supply of compressed air therethrough for operating the pump. This cap also has a guide 48 fitting guide pins 49 on the plate 12.

In the operation of the device, when the mold closes, the rod 13 turns the shaft 15 to straighten out the toggle formed by the parts 20 and 21 into the position shown in Figs. 1 and 2. In this position the gooseneck comes to a vertical position and the two nozzles 39 and 46 register with the two plates 40 and 47 so that air can be forced in through the latter and metal discharged into the mold through the former. The gooseneck is positively held in the proper position by the guides 48 and pins 49, as well as by the other mechanism above described, including the rods 19. When the mold opens and the rod 13 goes back, the shaft 15 is turned and the parts swing eventually to the position shown in Fig. 3. Here the crank arm 20 is swung upwardly and the link 21 brings the cradle back. The cradle swings on the combined system of pivots 26 and 28 and the nozzle 39 comes down into the position shown in Fig. 3 where it is under the level of the metal in the melting pot 11 and the gooseneck is filled by gravity.

In the construction of the parts it will be seen that the slides 17 are capable of moving back and forth freely so that expansion and contraction of the metal parts will not affect the action of this part of the device. The pump itself is easily removed from the cradle by loosening the screws 34 and 37 and just lifting it out. The other parts are easily disassembled. The screws 30 are adjusted to secure the necessary location of the gooseneck or pump for the purpose of filling the dies. This constitutes a simple motion for the gooseneck and provides ample guiding and adjusting devices for the purposes desired as well as ready detachability and safety from breakage due to expansion and contraction, which is necessary on account of the comparatively high heat required and its close association with the melting furnace.

Although I have illustrated and described only one form of the invention I am aware of the fact that modifications can be made therein by any person skilled in the art with-

out departing from the scope of the invention as expressed in the claims.

Therefore, I do not wish to be limited in these respects but what I do claim is:—

1. In a pneumatic metal pump, the combination with a shaft, freely slidable bearings on which the shaft is mounted and means for turning the shaft, of a cradle, a pneumatic pump carried by said cradle, and connections between the cradle and shaft for swinging the pump from a depressed and inclined position for filling to a vertical position for discharging the metal. 70

2. In a pneumatic metal pump for die casting machines, the combination with a frame and a cradle carried thereby for supporting the pump, of a shaft having a crank thereon pivotally connected with said cradle for moving the cradle and frame back and forth as the shaft turns, guides connected with the shaft on which the frame is slidably supported near one end and a pivotal connection pivoted at a stationary point for additionally supporting said frame. 80

3. In a pneumatic metal pump for a die casting machine, the combination with a movable frame having a cradle thereon and means on the cradle for supporting the pump, of a shaft having a crank connected with the cradle for moving the cradle and frame toward and from the shaft, a pair of guides radially connected with said shaft and slidably supporting said frame, a stationary pivot, and a link pivotally mounted on said pivot and pivotally connected with said frame for controlling the motion of the pump as the frame moves back and forth on said guides. 90

4. In a pneumatic pump for a die casting machine, the combination with a shaft having a crank thereon, and means for oscillating said shaft, of a link connected with said crank, a frame pivotally connected with the link, a pair of collars free to turn on said shaft, guide rods carried by said collars, said frame having passages therethrough for the rods and movable upon the rods, and means for pivotally supporting the frame at another point. 105

5. In a pneumatic pump, the combination with a melting pot having a stationary support, a lug projecting from said support, a pin connected with the lug, and a plate pivotally mounted on said pin, of a link pivotally connected with said plate, means for adjusting the ends of the plate up and down about the first named pivot, a frame depending from the upper end of said link and pivotally connected therewith, means for moving the frame back and forth and giving it a swinging motion, and a pneumatic pump carried 115 by said frame. 120

6. In a device for filling dies with molten metal, the combination with a melting pot, of a pneumatic pump located above the same, adjustable means for pivotally mounting the 130

- pump over the pot, a leverage system for lowering the pump into the pot and tilting it to allow it to be filled by gravity when submerged in the molten metal therein, said pump having two nozzles, one for discharging metal and the other for receiving air, a die plate having means for registering with both of said nozzles, supplying air to one, and receiving metal from the other, means for moving the cradle to bring the pump from the position in the melting pot up into position to receive air and discharge metal, and means to support said latter means for free movement under all conditions of expansion and contraction. 70
- 5 7. In a casting device, the combination with a melting pot, of an adjusting plate pivotally mounted thereon in substantially horizontal position, a link pivotally connected with said plate and extending upwardly therefrom, a cradle pivotally depending from the upper end of said link, said cradle being provided with rod receiving lugs, rods extending from the lugs on said cradle, a shaft 75 having means thereon for receiving the ends of the rods, a link operated by said shaft and pivoted to the cradle, and a pneumatic pump supported by the cradle, said cradle being connected with said frame to tilt down 80 into the melting pot when the frame is located in inclined position. 85
- 20 8. In a pneumatic metal pump for die casting machines, the combination with a frame and a cradle carried thereby for supporting the pump, of a shaft having a crank thereon pivotally connected with said cradle for moving the cradle and frame back and forth as the shaft turns, freely slidable bearings 90 on which the shaft and frame are slidably supported near one end and a pivotal connection pivoted at a stationary point for additionally supporting said frame. 95
- 25 9. In a pneumatic metal pump for a die casting machine, the combination with a movable frame having a cradle thereon, and means on the cradle for supporting the pump, of a shaft having a crank connected with the cradle for moving the cradle and frame toward and from the shaft, a pair of freely 100
- 30 10. In a pneumatic metal pump for die casting machines, the combination with a frame and a cradle carried thereby for supporting the pump, of a shaft having a crank thereon pivotally connected with said cradle for moving the cradle and frame back and forth as the shaft turns, guides connected with the shaft on which the frame is slidably supported near one end, freely slidable 105
- 35 11. In a pneumatic metal pump for a die casting machine, the combination with a frame and a cradle carried thereby for supporting the pump, of a shaft having a crank connected with the cradle for moving the cradle and frame toward and from the shaft, a pair of freely 110
- 40 12. In a pneumatic metal pump for die casting machines, the combination with a frame and a cradle carried thereby for supporting the pump, of a shaft having a crank thereon pivotally connected with said cradle for moving the cradle and frame back and forth as the shaft turns, guides connected with the shaft on which the frame is slidably supported near one end, freely slidable 115
- 45 13. In a pneumatic metal pump for die casting machines, the combination with a frame and a cradle carried thereby for supporting the pump, of a shaft having a crank thereon pivotally connected with said cradle for moving the cradle and frame back and forth as the shaft turns, guides connected with the shaft on which the frame is slidably supported near one end, freely slidable 120
- 50 14. In a pneumatic metal pump for die casting machines, the combination with a frame and a cradle carried thereby for supporting the pump, of a shaft having a crank thereon pivotally connected with said cradle for moving the cradle and frame back and forth as the shaft turns, guides connected with the shaft on which the frame is slidably supported near one end, freely slidable 125
- 55 15. In a pneumatic metal pump for die casting machines, the combination with a frame and a cradle carried thereby for supporting the pump, of a shaft having a crank thereon pivotally connected with said cradle for moving the cradle and frame back and forth as the shaft turns, guides connected with the shaft on which the frame is slidably supported near one end, freely slidable 130
